SNOW REMOVER

Caleb D. Rogers, Ellicott City, Md.

Application July 3, 1936, Serial No. 88,879

3 Claims. (Cl. 37—53)

My invention relates to new and useful improvements in snow removers or plows and more particularly to a device of this character adapted to be hand propelled and primarily intended for what might be termed home use for removing snow from sidewalks, roadways or the like although it will be understood that it might equally as well be used for removing snow from any point where a shovel or similar instrument is customarily used.

The principal object of the invention resides in the provision of a snow plow or remover of the character described which will be simple and inexpensive in construction, light in weight, and efficient in operation.

A further object of the invention resides in the provision of a snow plow or remover of the character described which is collapsible and which may be knocked down or collapsed for storage purposes or when shipping.

Another object of the invention consists in the provision of a snow plow or remover of the character described which is adjustable and adapted for cleaning a path through the snow of varying widths.

With the above and other objects in view, which will appear as the description proceeds, my invention consists in the novel details of construction and arrangement of parts, described in the following specification and illustrated in the accompanying drawing, and while I have illustrated and described the preferred embodiment of the invention, as they now appear to me, it will be understood that such changes may be made as will fall within the scope of the appended claims.

In the drawing:—

Fig. 1 is a top plan.

Fig. 2 is a side elevation.

Fig. 3 is a section on the line 3—3 of Fig. 2 looking in the direction of the arrows.

Fig. 4 is a longitudinal section on the line 4—4 of Fig. 1.

Fig. 5 is a longitudinal section on the line 5—5 of Fig. 1.

Fig. 6 is a transverse section through one of the wings or blades and a section of the connecting cross brace on the line 6—6 of Fig. 1; and

Fig. 7 is an enlarged fragmental detail of the front or pointed end of the plow or remover.

In carrying out my invention the entire remover or plow is formed of metal with the exception of the handle which may be of wood or metal as found most expedient. As shown more particularly in Figs. 1 and 3 of the drawing the plow

is of V-shape and includes the wings or blades 1 and 2 connected at their forward ends and angularly related to provide the V-shape previously described. Each of the blades is formed along its upper edge with an inwardly directed flange 3 and on its bottom edge with an inwardly directed flange 4 which is then bent or turned outwardly to provide an outwardly directed flange 5 which operates as a cutter in the movement of the plow or remover. The blade or wing 1 is formed on its forward end with an extension 6, the end of which is turned inwardly to provide a hook or parallel portion 7, as shown more clearly in Fig. 3 of the drawing. At its forward end the blade or wing 2 is provided with the extension 8 which is adapted to extend parallel with the extension 6 of the blade or wing 1 and this extension fits into the hook portion 7 as shown and the forward ends of the two blades or wings are detachably connected together by means of the bolts 9 and nuts 10, the bolts passing through the extensions 6 and 8 and the hook portion 7. As shown more particularly in Figs. 2 and 7 of the drawing, the upper edges of the blades or wings 1 and 2 are downwardly inclined from the rear ends towards the front ends to give a somewhat neater appearance and by doing this the wings or blades will be of increasing height from the front ends towards the rear ends. As also shown quite clearly in Figs. 2 and 7 of the drawing at the immediate forward ends the upper edges of the wings or blades 1 and 2 are beveled downwardly as shown at 11 while the bottom edges are inclined or beveled upwardly as shown at 12. This permits the remover or plow to more readily cut through the snow and the inclined or beveled portion 12 permits the device to ride over any obstructions or unevenness in the ground. As shown more particularly in Fig. 1 of the drawing the end of the flange 3 on the wing 4 or blade 1 overlies the flange 3 formed on the other wing or blade 2.

The wings or blades 1 and 2 are connected intermediate their ends by means of a cross brace which includes the vertically extending plate 13 provided with the upper flange 14 and the lower flange 15. The ends of the plate 13 are bent at an angle, as shown at 16, and these angular extensions extend parallel with the inner faces of the wings or blades 1 and 2 and the brace is secured to said wings or blades by means of the bolts 17 and nuts 18. The manner of connecting the brace to the wings or blades 1 and 2 is quite clearly shown in Figs. 3 and 6 of the drawing.

For propelling the remover or plow I provide a detachable handle which, as previously stated, may be of wood or metal. I have shown this handle as being formed in the sections 19 and 20, connected by the metal sleeve 21. This sleeve 21 is permanently secured to the section 19 by means of the downwardly bent prongs 22 and may be detachably connected to the section 20 by means of the bolt 23 and nut 24. As shown 5 more particularly in Fig. 5 of the drawing the adjacent ends of the handle sections are preferably beveled to facilitate assembling. The section 20, of the handle, passes through an opening 25 in the plate 13 of the cross brace 15 and is secured to this cross brace by means of a screw 26 which passes through the flange 14 of the brace and into the section of the handle. Preferably the handle, as well as the opening 25 will be square in cross section to prevent 20 turning of the handle. The forward end of the section 20 of the handle is preferably pointed or shaped as shown at 27 in Fig. 3 of the drawing and extends into the space between the blades or wings 1 and 2 at their forward ends. 25 The forward end of the handle is secured to the wings or blades by means of the screws 28 or other suitable fastenings.

In order that the angle of the wings or blades 1 and 2 may be adjusted I provide each with longitudinally spaced openings 29 through which the bolts 17, which connect the brace to the wings or blades, are passed. It will be understood that by moving the brace forwardly from the position in which it is shown it will have a tendency to 30 spread the blades or wings further apart. 35

From the above detailed description it is thought that the construction and manner of use will be clearly understood. By propelling the plow or remover through the snow the same will 40 be forced outwardly to provide a path and, as stated, the width of the path cleaned may be varied by adjusting the angle of the blades or wings. When it is desired to ship or to store the device may be collapsed or knocked down. 45 This is accomplished by removing the screws 28 and 26 so that the handle may be withdrawn through the opening 25 in the cross brace. By removing the nuts 18 from the bolts 17 the bolts may be removed to detach the cross brace from 50 the wings or blades. With this accomplished the blades may be detached by removing the nuts 10 from the bolts 9 and withdrawing the bolts. This permits the extension 8, on the forward end of

the blade or wing 2, to be withdrawn from the hook portion 7 of the blade or wing 1. The sections 19 and 20 of the handle may be disconnected by removing the bolt 23 which permits the section 20 to be withdrawn from the sleeve 21. The device is of simple construction, light in weight, and may be easily propelled through the snow for cleaning purposes. 5

Having fully described my invention what I claim as new and desire to secure by Letters Patent is:—

1. A snow remover of the character described including a pair of blades extending at an angle one relative to the other, one of said blades having its entire forward edge rebent to form spaced 15 parallel portions while the other blade is formed with an extension adapted to be positioned between the parallel portions, and means extending through the extension of the one blade and the parallel portions of the other blade for detachably connecting the blades at their forward ends. 20

2. A snow remover of the character described including a pair of blades extending at an angle one relative to the other, one of said blades having its entire forward edge rebent to form spaced 25 parallel portions while the other blade is formed with an extension adapted to be positioned between the parallel portions, means extending through the extension of the one blade and the parallel portions of the other blade for detachably connecting the blades at their forward ends, a brace positioned between and detachably connected to the blades, a handle extending through the brace with its end in engagement with the blades at their connected ends, means for detachably connecting the handle to the brace, and means for detachably connecting the handle to the blades. 30 35

3. A snow remover of the character described including a pair of blades extending at an angle 40 one relative to the other, means for detachably connecting the blades at their forward ends, a brace extending between and detachably connected to the blades, said brace having an opening intermediate its ends and furthermore provided with a flange along its upper edge, a handle 45 extending through the opening in the brace and beneath said flange, and means for detachably connecting the handle to the brace and to the blades at their connected ends, said means for connecting the handle to the brace extending through the flange thereof. 50
